Primary Examiner — L. A. Grabenstetter

CLAIM

The ornamental design for a phone holder as shown and described.

DESCRIPTION

FIG. 1 is a perspective view of the phone holder according to the invention, showing the top, front, and left side.

FIG. 2 is a perspective view of the phone holder showing the bottom, back, and right side.

FIG. 3 is a front view of the phone holder.

FIG. 4 is a rear view of the phone holder.

FIG. 5 is a right side plan view of the phone holder.

FIG. 6 is a left side plan view of the phone holder.

FIG. 7 is a top view of the phone holder; and,

FIG. 8 is a bottom view of the phone holder.

The broken lines are for the purpose of illustrating the environment of the article only and form no part of the claimed design.

1 Claim, 6 Drawing Sheets
